BOOKBINDING

William H. Talley, Tulsa, Okla.

Application July 28, 1938, Serial No. 221,831

9 Claims. (Cl. 281—29)

This invention relates to a bookbinding and it is one object of the invention to provide a binding by means of which pages of a book may be bound between stiff covers through the medium of links carried by the covers and a backing strip and passing through registering openings formed in the guards, the links being so formed and so connected with the stiff covers and the backing strip that the book may be opened very easily at any page and the leaves disposed flat in a substantially horizontal plane.

Another object of the invention is to so form the links that, when the book is opened, the links may be extended longitudinally and also sections 15 of the links pivoted relative to each other and thus permit yielding movement which will allow the book to be easily opened at any page and disposed flat upon a desk when opened.

Another object of the invention is to provide 20 a binder wherein improved means has been provided for connecting hinge strips with opposite side edge portions of the backbone of a stiff backing strip and thus permit a backing strip of the proper width to be used according to the 25 thickness of the book to be bound.

The invention is illustrated in the accompanying drawings, wherein

Figure 1 is a view looking down upon a book 30 of the improved construction with the covers in a horizontal position for resting upon a table and a stack of leaves extending vertically from the backing strip between the covers, a portion of the stack of leaves being broken away,

Figure 2 is a view showing the covers and the 35 backing strip and companion hinge strip separated from each other,

Figure 3 is a sectional view taken along the line 3—3 of Figure 1,

Figure 4 is a view similar to Figure 3 but showing the book opened at one of its pages.

Figure 5 is a sectional view taken longitudinally through one of the hinged posts, the view being along the line 5—5 of Figure 6,

Figure 6 is a plan view of the post shown in 45 Figure 5,

Figure 7 is a fragmentary sectional view taken along the line 7—7 of Figure 4, and

Figure 8 is a plan view of a modified form of post.

50 The book which is bound in accordance with this invention has a stack of sheets or leaves 1 disposed between stiff covers 2 and between the stiff covers is a stiff backing strip 3 which is curved transversely, as shown in Figures 3 and 4, 55 and includes in its construction a fiber backbone

3'. Anchoring strips 4 which are formed of stiff metal extend along side edge portions of the fiber backbone 3' where they are secured by a suitable number of rivets 5, and each of the anchoring strips has portions struck up to define spaced tongues 6 which project from the anchoring strips, as shown clearly in Figures 3 and 4. The tongues or lugs 6 are of sufficient length to be passed through slots 7 formed in hinge strips 8 and, when the ends of the tongues 10 are bent over after being passed through the slots, the hinge strips will be firmly secured along opposite side edge portions of the fiber backbone with their hinge loops or ears 9 along their outer side edges. When a book consisting of four or 15 more quires of sheets is to be bound, a metal backbone may be used instead of the fiber back and have its side edge portions cut to form the tongues 6. In this embodiment of the invention, the strips 4 will be omitted as the metal backbone is cut to form the tongues.

The hinge ears 9 are to engage between the hinge ears 10 of hinge strips 11 which extend along side edge portions of the covers 2 and are firmly secured thereto by a suitable number 25 of rivets 12. Pivot rods or pins 13 are passed through the hinge ears 9 and 10, and when these rods are in place, the covers and the backing strip 3 will be hinged together, and the covers may be disposed in substantially a horizontal 30 position flat upon a desk or table when the book is opened.

The leaves consist of the usual groups of folded sheets, and these groups are sewed to guards 14 which may be secured in stacked formation by 35 binding strips or in any other conventional manner and through these guards extend hinged posts or binders. Upon referring particularly to Figures 3 and 4, it will be seen that the binders pass through registering openings formed in the 40 guards, as shown at 14. The binders may be formed as shown in Figures 5 and 6 where each binder consists of a pair of links 15 having their inner ends formed with hinge ears 16 to receive a pivot pin 17 or if longer binders are necessary 45 each may consist of end links 18 and one or more intermediate links 19 hinged to inner ends of the end links, as shown at 20 in Figure 8. The end links 15 or 18 are of a flat tubular formation and each has one wall cut to form a 50 tongue 21 which is bent inwardly, as shown in Figure 5, and, since the links are formed of resilient metal, terminal links 22, which are referred to as hinge links may be forced inwardly through outer ends of the links 15 or 18. The 55

inner ends of the tongues 21 will spring into the slots 23 formed in the hinge links longitudinally thereof, and thus will be slidably mounted in the end links for shifting movement therein during opening or closing of the book. The hinge links will be prevented from moving entirely out of the end links 15 and 18 by the tongues 21. Sleeves or loops 24 are formed at outer ends of the hinge links and these loops are disposed 5 between certain of the hinge ears 9 of the hinge strips 8 so that the pins 13 may pass through the sleeves 24 and hingedly mount ends of the links 22 between the hinge strips 8 and 11.

When a book is bound in accordance with this 15 invention, the stacked leaves will be held in place between the covers by the hinged expanding posts which pass through the registering openings 14 of the guards. When the book is to be opened, it is placed upon a desk or table and the covers 20 2 will rest upon the table in substantially a horizontal position and the backing strip 3 will also rest upon the table. During opening of the book, the hinge links 22 will slide outwardly through the end links of the binders and, when the book 25 is opened at a desired page, the links 15 or 18 may have pivotal movement at their inner ends and move from the position shown in Figure 3 to a position in which they extend diagonally from each other at a downward incline, as shown 30 in Figure 4. The book will then be fully opened at the desired page and the leaves will extend substantially horizontally. The links 15 or 18 are hingedly mounted at their inner ends and the hinge links 22 are slidably received in the 35 links 15 or 18 so that the binders may be extended longitudinally and permit the book to be very easily opened or closed and cause the leaves to extend horizontally when opened and not have a tendency to move towards a closed 40 position when the book is opened.

Having thus described the invention, what is claimed as new is:

1. In a bookbinding, leaves, guards connected therewith and having registering openings, covers, a backing, hinge strips carried by the backing and the covers and provided with interfitting hinge ears, binders extending through the registering openings of said guards and consisting of pivotally connected links and terminal links, 45 the terminal links being shiftable longitudinally of the first mentioned links and having hinge loops at their outer ends disposed in interfitting relation to certain of the hinge ears of the hinge strips carried by said backing, and pins extending 50 through the interfitting ears to pivotally connect the hinge strips and terminal links.

2. A bookbinding comprising a backing, hinge strips mounted along opposite side edge portions of the inner face of said backing and having 55 hinge ears along their outer side edges, covers, hinge strips secured along rear side edge portions of said covers and having hinge ears along their outer side edges disposed for interfitting engagement with the hinge ears of the first-mentioned 60 hinge strips, pins extending through the hinge ears to pivotally connect said covers with said backing, and binders passing through guards of a stack of leaves and extending transversely 65 across the inner face of said backing, each of said binders consisting of a plurality of links pivoted to each other, certain of said links being end links, the end links being of flattened tubular 70 formation and open at their outer ends, terminal links slidably engaged in the end links and formed 75 with longitudinally extending slots, the end links

having tongues cut therefrom and bent inwardly to provide resilient latches engaged through the slots of the terminal links, and hinge loops at outer ends of the terminal links, the hinge ears of the terminal links being disposed between certain of the hinge ears of the hinge strips carried by said backing with the pivot pins passing through the same to pivotally mount the binders at their ends.

3. In a bookbinding, a backing, anchoring strips secured along opposite side edge portions of said backing, tongues extending from said anchoring strips, hinge strips disposed against the anchoring strips and formed with openings, said tongues being passed through the openings and bent to clinch the hinge strips against the anchoring strips, hinge ears spaced from each other along outer side edges of said anchoring strips, covers, hinge strips secured along rear side edge portions of said covers and having hinge ears fitting between the hinge ears of the first hinge strips, pins extending through the hinge ears to pivotally connect the hinge strips and mount the covers for swinging movement from a closed position to an opened position, and binders extending transversely across the inner face of said backing.

4. In a permanent bookbinding, a backing, covers, hinges connecting said covers with said backing, and binders passing through sewed on guards of a stack of leaves, said binders being disposed transversely across the inner face of said backing and each consisting of a plurality of pivotally connected links, certain of said links being hollow and open at their outer ends and other links being slidably engaged in the hollow links and formed with longitudinally extending slots, hinge ears pivotally engaged with said hinges and tongues carried by the hollow links and engaged through the slots of the last-mentioned links to slidably mount the last-mentioned links and limit longitudinal sliding movement thereof.

5. In a permanent bookbinding, a backing, covers, hinges connecting said covers with said backing, and binders passing through guards of a stack of leaves, said binders being disposed transversely across the inner face of said backing and each comprising links pivoted to each other, terminal links in telescoping engagement with the pivoted links, and resilient latches for limiting sliding movement of the last-mentioned links.

6. In a permanent bookbinding, a backing, covers, hinges connecting said covers with said backing, and binders passing through guards of a stack of leaves, said binders extending transversely across the inner face of said backing and each comprising flat links pivoted to each other, said links being hollow and open at their outer ends and having their walls cut to form tongues projecting inwardly and extending longitudinally of the links towards inner ends thereof, and terminal links pivoted to said hinges and slidably received in the hollow links and formed with longitudinally extending slots through which said tongues engage to limit longitudinal sliding of the terminal links in the hollow links.

7. In a bookbinding, a backing strip, an anchoring strip, means for securing the anchoring strip to the backing strip, and tongues extending from the anchoring strip, said tongues being engageable through openings in a hinge strip and being bent for securing the hinge strip to the backing.

8. In a bookbinding, a backing, an anchoring strip, means securing the anchoring strip to the backing, said anchoring strip having portions

thereof struck up to define tongues, a hinge strip having openings receiving the tongues therethrough, said tongues being bent to engage the hinge strip with the anchoring strip and backing, covers, and means swingingly connecting the covers with the hinge strip.

5. 9. In a bookbinding, a binder consisting of a pair of end links, means pivotally connecting the end links to each other at their confronting ends,

said end links being of tubular formation and open at their outer ends, said end links having tongues struck therefrom to define latches, and terminal links slidably mounted in the end links and having longitudinal slots receiving the latches therein, said latches and slots cooperating for restricting sliding movement of the terminal links.

WILLIAM H. TALLEY.
